UNITED STATES PATENT OFFICE.

DANIEL S. REGAN, OF SAN FRANCISCO, ASSIGNOR TO HIMSELF, AND SANFORD S. BENNETT, OF ALAMEDA, CALIFORNIA.

GOVERNOR FOR GAS-ENGINES.

SPECIFICATION forming part of Letters Patent No. 397,753, dated February 12, 1889.

Application filed April 4, 1888. Serial No. 269,630. (No model.)

To all whom it may concern:

Be it known that I, DANIEL S. REGAN, a citizen of the United States, and a resident of the city and county of San Francisco, and State 5 of California, have invented certain new and useful Improvements in Governors for Gas-Engines, of which the following is a specification.

My invention relates to governors for gas- 10 engines.

Figure 1 is a side elevation of the governor, showing its attachment to the main shaft, which is shown broken off; Fig. 2, an inside view of the same, showing the operating-gear; 15 Fig. 3, an outside view showing the position of the crank and piston of the engine and the end of the shaft, with the position of the gear denoted by dotted lines.

The following is the construction of my im- 20 proved governor:

I form the sleeve and inside gear, A, and the wheels gearing with the same of metal and finish the same smoothly, as that class of machinery is generally finished. I attach the 25 cams B and C upon the periphery of the wheel A, for the purpose of operating the valve-levers D and E to open and close the valves. F represents the inside spur gear or teeth of the wheel A. The main spur-wheel upon the 30 crank-shaft S is represented by the letter G, and the intermediate gear by the letter H. I attach the collar I, which contains the hinge-arms J and K, firmly to the main shaft. I attach the governor-balls L and M and levers O 35 and P by pivoting them.

Attached to the gear-wheel A is the grooved collar Q, by means of which groove the governor-levers O and P connect for the purpose of moving the gear-wheel A in and out suffi- 40 ciently to connect and disconnect the cams C with the lever E. I construct the gear F suffi- 45 ciently wide to allow the required sliding upon the intermediate wheel, H, and allowing the connecting and disconnecting of the cam C and the lever E, as will be more fully explained by the operation of the same.

The action of the governor-balls is similar to those of other ball-governors.

It will be seen that the wheel A, with cams 50 B and C, and connecting-collar Q, with groove R, are allowed to slide out and in upon the

shaft S and to revolve independently of the movement of the same.

T represents the piston, and U the pitman or connecting-rod of the engine; V, the cyl- 55 inder.

X and Y represent the anti-friction rolls of the valve-levers.

The following is the operation of my im- 60 proved governor: It will be seen that the ob- ject is to secure the action of both the exhaust and supply valve once in two revolutions, and to that end the operating-gear F, G, and H are so proportioned that the wheel A is made to revolve once while the wheel G and shaft 65 S make two revolutions. As the main or crank shaft S is revolved, the piston is moved out and in the cylinder. The first outward stroke fills the cylinder from any suitable gas and air supply, as other engines are supplied 70 with a charge of gas and air by suitable connecting-pipes and check-valves. As the crank continues to revolve and the piston is forced in, compressing the gas, the electric spark or other igniting heat is produced and the 75 charge ignited, and the piston is forced out, expending its force upon the crank of the engine. The crank continuing to revolve, the cam B having reached the exhaust-lever D, the exhaust is opened and held open until the 80 piston has reached the end of the back-stroke and the exhaust is completed, the cam B having then passed the end of the lever D, and the exhaust-valve again closes. The supply- 85 valve is then opened as the cam C comes in contact with the lever E, and remains open until the outward stroke of the piston is made and one-fourth revolution of the wheel A is made. The cylinder is now full, and as the 90 piston passes back the charge is compressed and ignited and the piston forced out, as be- 95 fore, giving its force to the crank of the engine. It will be seen that the cams B and C each occupy one-fourth of the circumference of the wheel A, which corresponds to the time taken for one half-stroke of the piston, thus 95 securing two revolutions to each action of the supply and exhaust valves.

The action of the governor is as follows: As the speed of the shaft is accelerated, the balls 100 L and M are thrown out and the lever-arms O and P draw the wheel A out, and the cam C

is drawn out farther than the lever E. The lever E then has a bearing the whole circumference of the wheel A, thus omitting the operation of the supply-valve until the speed of 5 the engine is brought down to what is required. I generally employ anti-friction rolls X and Y for the bearing of the ends of the valve-rods, as shown.

Having thus described my invention, what I 10 claim, and desire to secure by Letters Patent, is—

1. In a gas-engine, a ball-governor having the hinged arms J and K attached to the fixed collar I, the sleeve and inside gear-wheel, A, 15 having the collar Q, with groove R, the con-

necting-levers O and P, and cams B and C, in combination with the valve-levers D and E, constructed and operated substantially as and for the purposes set forth.

2. In a gas-engine, a governor having a sliding gear-wheel, A, the inside spur-gear, F, the fixed gear G on shaft S, and the intermediate gear, H, in combination with the cams B and C, for the purpose of operating the valve-levers D and E, constructed and operated substantially as and for the purposes set forth. 20 25

DANIEL S. REGAN.
